UNITED STATES PATENT OFFICE.

GREEN B. WILLIAMS, OF LONG LANE, MISSOURI.

REGISTERING WIRE-STRETCHER.

1,208,065.

Specification of Letters Patent. Patented Dec. 12, 1916.

Application filed June 1, 1916. Serial No. 101,101.

To all whom it may concern:

Be it known that I, GREEN B. WILLIAMS, a citizen of the United States, residing at Long Lane, in the county of Dallas, State 5 of Missouri, have invented certain new and useful Improvements in Registering Wire-Stretchers; and I do hereby declare the following to be a full, clear, and exact description of the invention, such as will enable 10 others skilled in the art to which it appertains to make and use the same.

This invention relates to a registering wire stretcher.

An object of the invention resides in the 15 provision of an improved device of this character by means of which the wires of a fence may be stretched.

A further object of the invention resides in so-constructing the device that the wires 20 of the fence may be stretched by the same force and so that that force will be indicated to the operator.

A further object of the invention resides in so-constructing the device that the wires 25 of the fence may be stretched conveniently by one operator.

With these and other objects in view, such as will appear as my description progresses, my invention comprises the combination and 30 arrangement of parts as set forth in and falling within the scope of the appended claim.

In the drawing: Figure 1 is an elevational view of a device constructed in accordance 35 with my invention; Fig. 2 is a longitudinal sectional view; Fig. 3 is a transverse sectional view showing the take-up mechanism, and Fig. 4 is a similar view taken on line 4-4 of Fig. 2.

The embodiment of the invention illustrated in the drawing includes a tubular casing 1 which is open at one end and is provided with a pair of guide arms 2 which carry a guide eye 3. Extending transversely 40 of the casing 1 within the same is a bar 4 to which one end of a helical spring 5 is attached, which spring extends longitudinally of the casing and is provided on the other end with a pointer 6 which extends through a slot 7 in the casing and co-operates with a 45 series of numbers 8 to indicate the force in pounds which is applied to the spring. A

rod 9 is secured to the end of the spring adjacent to the pointer 6 and extends through a guide eye 10 which is mounted in the open 55 end of the casing 1. A chain 11 is secured to this rod 9 and is provided with a wire engaging hook 12 for attachment to the wire which is to be stretched.

Extending transversely of the casing 60 within the same and parallel to the bar 4 is a shaft 13 on which a drum 14 is secured. A flexible attaching member 15 is secured to and windable on this drum and extends through the guide eye 3 for attachment to a 65 permanent member such as a tree or a post. A ratchet 16 is secured to this shaft 13 and co-operates with a pawl 17 to prevent the movement of the shaft in one direction. The shaft is provided with a crank handle 70 18 by means of which it may be cranked.

In operation the member 15 is attached to a tree or post and the member 12 to the wire which is to be stretched. As the handle 75 18 is turned the member 15 will be wound upon the drum 14 so that the wire will be stretched. As the wire is stretched the pointer 6 will move from one to the other of series of numbers 8 so as to indicate the force in pounds which is exerted upon the 80 wire to stretch the same. It is obvious that this presence of the pawl and ratchet on the winding drum shaft will permit the operator to release the handle 18 while he reads the register so that he may determine the 85 force to apply to the remaining wires.

While I have illustrated and described a particular embodiment of my invention, it has merely been for the sake of convenience and I do not wish to be limited to that particular embodiment as it is obvious that numerous changes may be made in the details of construction without departing from the spirit of the invention or exceeding the scope of the appended claim.

What I claim is:

In a wire stretcher, the combination with a tubular casing, of a winding drum mounted adjacent one end thereof and within the same, a flexible attaching member secured to and windable on said drum, means for preventing the rotation of the drum in one direction, a bar extending transversely of the casing, a spring connected to the bar and a

wire engaging member associated with the
spring, the said spring having a pointer on
one end thereof and the casing having a
series of numbers thereon which coöperate
with the pointer to indicate the force ap-
plied to the spring.

In testimony whereof, I affix my signa-
ture, in the presence of two witnesses.

GREEN B. WILLIAMS.
